ATTORNEY.

UNITED STATES PATENT OFFICE.

GEORGE WALKER GILMER, JR., OF PHILADELPHIA, PENNSYLVANIA.

COMBINATION-TOOL.

1,074,113.

Specification of Letters Patent. Patented Sept. 30, 1913.

Application filed September 17, 1912, Serial No. 720,777. Renewed August 15, 1913. Serial No. 784,972.

To all whom it may concern:

Be it known that I, GEORGE WALKER GILMER, Jr., a citizen of the United States, residing in the city of Philadelphia, county of 5 Philadelphia, and State of Pennsylvania, have invented certain Improvements in Combination-Tools, of which the following is a specification.

My invention is a combination tool de-10 signed for use as a spreader and as pliers. It is useful particularly for spreading an opening, as in a punctured tire, but it is also adapted for gripping, as in holding or turning various devices, being particularly use-15 ful in turning a device in a difficultly accessible place.

The preferred construction of my invention comprises a lever having a jaw and a species of loop forming handles connected 20 by a rack, in combination with a lever having a jaw coöperating with the jaw first named and a dog coacting with the rack to hold the jaws in separated relation.

The device is produced economically and 25 satisfactorily from sheet material cut and bent to form.

In the accompanying drawings, Figure 1 is a plan view of a tool embodying my improvements; Fig. 2 is a sectional view taken 30 on the line 2—2 of Fig. 1; and Fig. 3 is a sectional view taken on the line 3—3 of Fig. 1.

The tool, as illustrated in the drawings, comprises a lever consisting of the curved 35 arm 1 with the jaw 2 thereon and the handles 3 connected by the member 4 having the rack 5 thereon, this lever being produced from sheet metal cut and bent to form with the production of a construction of chan-40 neled or substantially U-shaped cross section. A second lever, pivoted to the first lever by the pintle 10, has the curved arm 1' with the jaw 2' thereon which coöperates with the jaw 2, and the arm 3' containing a 45 notch 3'' for the passage of the rack 5, the extension 3''' of this arm bearing in the channel of the arm 3 to steady the movement. A latch or dog 4' is fulcrumed on the arm 3' by the pin 3^a and held in engagement 50 with the rack 5 by the coiled spring 3^b. This lever is also formed by cutting and bending

sheet metal so as to provide a construction having a channeled or substantially U-shaped cross section.

I prefer connecting the arms 1 and 3 by 55 the comparatively broad intermediate section 6 and the arms 1' and 3' by the comparatively broad intermediate section 6', thereby providing bearings of requisite strength. A washer or bearing plate 7 is disposed be-60tween the bearings 6 and 6' and a washer 8 is disposed within the flanges 6'' of the bearing 6'.

In operation, in spreading an opening, the closed jaws 2 and 2' can be inserted therein 65 and the handle 3' moved toward the appropriate handle 3 to spread the jaws, the latch 4' slipping over the inclined faces of the rack teeth and holding the jaws expanded to the desired degree by engagement with a 70 vertical face thereof, the latch being released from the rack, to permit the free movement of the handle 3', by rocking it against the action of the spring 3^b.

Having described my invention, I claim: 75

1. A tool comprising a pair of pivotally connected levers having coöperative jaws for spreading an opening and handles for operating said jaws, one of said jaws having a pair of said handles provided with a connecting member and the other of said jaws having one of said handles adapted to coöperate with said member for holding said jaws in the desired relation. 80

2. A tool comprising a pair of pivotally connected levers provided with coöperative jaws, one of said levers being provided with a pair of handles and a rack disposed between said handles, and the other of said levers being provided with a handle having 90 a latch coacting with said rack.

3. A tool comprising a pair of pivotally connected levers having coöperative jaws, one of said levers having a loop comprising handles and the other of said levers having an arm adapted to oscillate between the limits of said handles, said loop and arm having means connected therewith whereby they can be fixed to hold said jaws in a desired 95 relation.

4. A tool comprising a pair of pivotally connected levers formed of sheet metal bent 100

to form a substantially U-shaped cross section, one of said levers having handles connected by a part provided with a rack and the other of said levers having a spring 5 pressed latch movable over said rack.

5. A tool comprising a pair of levers having coöperative jaws disposed at an angle thereto, sheet metal handles of substantially U-shaped cross section, and broad bearings

on which said levers oscillate connecting said 10 jaws and handles respectively.

In witness whereof I have hereunto set my name this 23rd day of August, 1912, in the presence of the subscribing witnesses.

GEORGE WALKER GILMER, JR.
